UNITED STATES PATENT OFFICE

STERLING H. CAMPBELL, OF ST. LOUIS, MISSOURI.

ANGLE-COCK HOLDER FOR RAILWAY-CARS.

1,031,419.

Specification of Letters Patent.

Patented July 2, 1912.

Application filed January 6, 1912. Serial No. 669,892.

To all whom it may concern:

Be it known that I, STERLING H. CAMPBELL, a citizen of the United States, residing at St. Louis, Missouri, have invented a certain new and useful Angle-Cock Holder for Railway-Cars, of which the following is such a full, clear, and exact description as will enable any one skilled in the art to which it appertains to make and use the same, reference being had to the accompanying drawings, forming part of this specification.

My invention relates to an angle cock holder for railway cars, and its object is to provide a holder which will be simple in construction and effective in operation and which will not be liable to get out of order by loss of parts.

In the accompanying drawings, which illustrate two forms of holders made in accordance with my invention, Figures 1 and 2 are a front and side elevation, respectively, of the holder and an angle cock carried thereby; Figs. 3 and 4 are views similar to Figs. 1 and 2, but showing the holder alone; Figs. 5 and 6 are views similar to Figs. 1 and 2, but showing a slight modification, and Fig. 7 is an isometric projection of one of the parts shown in Figs. 5 and 6.

Like marks of reference refer to similar parts in the several views of the drawings.

10 represents a flange which is made of such form as to leave a hexagonal opening 11 adapted to fit the hexagonal head 12 of an angle cock which is carried by the train pipe 13. The flange 10 is provided with four contact points, namely, an upper pair 14 and a lower pair 15, as best shown in Figs. 2 and 7. These contact points 14 and 15 are curved so as to fit the body 16 of the angle cock and thus limit its rearward movement. In order to secure the angle cock against forward movement, I provide the flange 10 with openings 17 adapted to receive a cotter pin 18, which cotter pin is adapted to bear against the front face of the angle cock head 12 and thus prevent the forward movement of the angle cock.

It will be evident that the insertion of the cotter pin firmly locks the angle cock in position, as the contact points 14 and 15 prevent its rearward movement and the cotter pin itself prevents its forward movement.

55 In order to secure the holder to a railway

car I provide the flange 10 with an integral plate 20 having formed at right angles thereto a second plate 21. These two plates 20 and 21 together form a bracket by means of which the holder is bolted to the end sill 22 by means of bolts 23 and nuts 24, as shown in Figs. 1 and 2.

In Figs. 5, 6 and 7 I have shown a modification in which the flange 10 is provided with the contact points 14 and 15 and with the holes 17 for the cotter pin, in the same manner as the form above described. In this modification, however, the flange 20 is dispensed with and in its place the holder is provided with a flange 25 arranged at right angles to the flange 10 and preferably entirely surrounding the same. In this construction the member composed of the flanges 10 and 25 is inserted in a suitable hexagonal opening in a plate carried by the car. As shown in Figs. 5 and 6, this plate is the end sill 22. In order that the member composed of the flanges 10 and 25 must be placed in the opening of the end sill 22 in the proper position, I provide the said member with a projection 26 which is preferably arranged at one corner of the hexagon and I provide the opening in the end sill 22 with a similar extension 27 adapted to receive the projection 26, as best shown in Fig. 6. This insures the proper positioning of the member in its opening. It will be evident that the flange 25 prevents the withdrawal of the member through the opening in the end sill. At the same time, this form of my invention allows a certain amount of play between the car and the angle cock. This play will compensate for the relative variation in the length of the train pipe and car due to cambering, and thus reduces the strain upon the joint between the train pipe and angle cock.

It will be evident that in my device there is therefore no chance for loss of parts which would disable the device. In both forms the holder itself consists of but a single casting, and the cotter pin which holds the angle cock in position in the holder is not liable to become lost, and, even if lost, it may be readily replaced by a nail or wire of the proper size.

I claim:

1. In an angle cock holder, a member provided with a flanged opening adapted to receive the head of the angle cock and pre-

vent its rotation, said flange forming a plurality of contact points bearing on the body of the angle cock.

2. In an angle cock holder the combination with an integral member provided with an angular opening adapted to allow the passage of the head of the angle cock but to prevent its rotation, said integral member completely surrounding the head of the angle cock and a removable abutment carried by said member and adapted to engage with the front of the angle cock head.

3. In an angle cock holder the combination with an integral member provided with an angular opening adapted to receive the head of the angle cock, said member being provided with a flange, of contact points bearing on the body of the angle cock, and a removable abutment carried by said member and adapted to engage with the front face of the angle cock head.

4. In an angle cock holder the combination with a member provided with an angular opening adapted to receive the head of an angle cock and prevent its rotation, of a plate having an opening to receive said member, a fixed abutment carried by said member for engaging the rear of said plate, and a removable abutment carried by said member for engaging with the front face of the angle cock head.

5. In an angle cock holder the combination with a flanged opening adapted to receive the head of an angle cock and prevent

its rotation, and a pin passing transversely through the flange and forming a removable abutment engaging with the front face of the angle cock head.

6. In an angle cock holder the combination with a member provided with a flanged opening adapted to receive the head of an angle cock and prevent its rotation, said flange forming a plurality of contact points bearing on the body of the angle cock, of a pin passing transversely through said flange and forming a removable abutment to engage with the front face of the angle cock head.

7. In an angle-cock holder, the combination with a member provided with an opening adapted to receive the head of an angle cock and prevent its rotation, said member comprising a flange and an abutment, said flange forming a plurality of contact points bearing upon the body of the angle-cock, of a plate having an opening to receive said member, said abutment bearing against the rear of said plate, and a pin passing transversely through said flange and forming a removable abutment for engaging the front face of the angle-cock head.

In testimony whereof, I have hereunto set my hand and affixed my seal in the presence of the two subscribing witnesses.

STERLING H. CAMPBELL. [L. S.]
